UNITED STATES PATENT OFFICE.

JOHN G. GILMER, OF OXFORD, ASSIGNOR OF ONE-THIRD TO MARIAN P. SELLMER, OF ZELLWOOD, FLORIDA.

GRAIN-BINDER.

SPECIFICATION forming part of Letters Patent No. 443,176, dated December 23, 1890.

Application filed August 30, 1890. Serial No. 363,465. (No model.)

To all whom it may concern:

Be it known that I, JOHN G. GILMER, a citizen of the United States, residing at Oxford, in the county of Sumter and State of Florida, have invented a new and useful Grain-Binder, of which the following is a specification.

This invention has relation to grain-binder attachments for harvesters, and relates to that class thereof in which the band is formed from the gavel—in other words, from the grain itself during the operation of building the bundle.

The objects and advantages of the invention, together with the novel features thereof, will hereinafter appear, and the latter particularly pointed out in the claims.

Referring to the drawings, Figure 1 is a plan of a binder attachment constructed in accordance with my improvement. Fig. 2 is a similar view, the platform removed. Fig. 3 is a longitudinal vertical section. Fig. 4 is a similar view, the tucker being in the act of tucking. Fig. 5 is a transverse section looking toward the twister. Fig. 6 is a transverse section in the opposite direction. Fig. 7 is a side elevation. Fig. 8 is a detail in perspective of the clamping-arms and their shaft and support. Fig. 9 is a perspective of the tucker. Fig. 10 is a longitudinal section of the twister. Fig. 11 is a detail in elevation of the cam-pulley operating the clamping-arms.

Like numerals of reference indicate like parts.

In practicing my invention I locate the mechanism hereinafter described in an oblong frame consisting of opposite front and rear side bars 1, connecting end bars 2, and a central longitudinal bar 3, said frame being suitably supported in the usual manner and as will be readily apparent to those skilled in the art. In transversely-opposite bearings 4, located upon the under side of the rear side bars and the central bar, there is journaled the main power-shaft 5, which extends beyond the rear bearing and is there provided with the toothed gear 6. The gear 6 has its periphery toothed only for about two-thirds its length, the remaining portion being plain or untoothed, as at 7. Beyond the gear 6 a pulley 7 is mounted upon said shaft, which pulley receives motion from the operating

mechanism of the binder. Between its bearings the shaft 5 is provided with a cam-pulley 8, provided with a cam pin or lug 9, extending from the inner face of the same. 55

Upon a headed lug 10, extending from the inner face of the adjacent side bar 1, there is loosely mounted a tucker-arm 11, slotted longitudinally at its rear end, as at 12, whereby it is adapted for both a pivotal and reciprocal movement upon the stud 10. The tucker-arm is laterally and inwardly bent to pass inside of the cam 8, and upon its under side opposite the cam is provided with a cam-recess 13, which terminates at its inner end in an abrupt shoulder 14. Beyond the cam-recess the tucker-arm is horizontally and then upwardly bent or disposed and terminates in a tucking-finger 15.

At one side of the shaft 5 there is journaled in bearing 16 a counter-shaft 17, the ends of which extend beyond the bearings, and at its outer end is provided with a small pinion 18, adapted to be intermittently operated by the gear 6, and at its inner end is provided with a small beveled pinion 19.

In longitudinally-opposite bearings 20, secured to the under side of the opposite end bars near the front of the frame-work, is a longitudinal shaft 21, the ends of the shaft 80 extending beyond the bearings and provided at one end with a gear 22 and at the opposite end with similar gear 23. Within its bearings and nearly opposite the shaft 17 there is mounted upon the shaft 21 a beveled pinion 24, which engages and is driven by the pinion 19. Near the opposite bearing there is located a sprocket-wheel 25.

In one of the end bars of the frame-work there is seated a journal or bearing 26, in which is mounted one end of a stub-shaft 27, the opposite end being journaled in a bracket 28, secured to the frame-work. Between its bearings the shaft carries a small pinion 29, which is engaged and driven by a large pinion 30, in turn engaged and driven by the gear or pinion 22. Upon the inner end of the stub-shaft there is secured a hollow tube 31, spirally slotted from end to end, as at 32, and terminating in the slightly outward bent finger 33.

34 designates an outer hollow tube which

surrounds and loosely fits the tube 31, and said tube 34 is spirally slotted, as at 35, in the direction opposite to the slot 32. The outer tube 34 is stationary, while the inner tube 31 is adapted to revolve, and the former-mentioned tube is supported by a bracket 36, secured to the end bar of the binder. Each of these tubes forms what I term a "twister-section," and the two combine to form the band 10 forming twister, which terminates at one side of and directly over the tucking-finger here-tofore mentioned.

37 designates a standard provided at its upper end with a bearing and mounted upon 15 the end bar of the frame-work opposite the one upon which is mounted the twister. In this standard is journaled a short shaft 38, the ends of the shaft extending beyond the bearing and its outer end supported by a bearing-bracket 39, secured to the end bar of the frame-work. A gear 40 is mounted upon the shaft between its two bearings, which gear is engaged and driven by a large gear 41, mounted upon the shaft 42 and driven by the 20 gear 23. Upon the inner end of the shaft 38 is mounted a sprocket-gear 43, which by a chain 44 is connected with and driven by the small sprocket 25. At one side of the sprocket, and in this instance formed integral therewith, is a cam-wheel 46, having a cut-away portion 47, as shown.

48 designates a crank or L-shaped arm, also mounted upon the shaft 38, and is provided at opposite ends with bearings 49, in 35 which is journaled a rock-shaft 50. The rock-shaft 50 extends beyond its bearings, and at its outer end is provided with a cam-arm 51, maintained in contact with the surface of the cam-wheel 47 by means of a coiled spring 52, 40 which encircles the rock-shaft and has one end secured thereto and to the crank-arm. The inner end of the rock-shaft has fixed thereupon a curved gavel-clamping arm 53, and at one side of the shaft there is rigidly 45 secured to the crank-arm a companion gavel-gripping arm 54.

55 designates the platform which covers that portion of the frame-work unoccupied by the twister, the gavel-gripping arms, and 50 the crank-arm, said platform being provided with a slot 56 at its inner edge for the passage of the crank-arm and with an opening 57 for the sprocket-chain 44.

58 designates a bracket secured to the under side of one of the side rails, and to the same is secured one end of a coiled spring 59, the opposite end of which is secured to the rear end of the tucker-arm, whereby said arm is spring-pressed toward the opposite end of 60 the machine, or, in other words, toward the twisting mechanism.

This being the construction, the operation is as follows: Beginning with the time that a sheaf is formed, the gripping-arm, by the action of the cam-arm upon the cam 46 and by reason of said cam-arm coming opposite the cam portion 47 of the cam-wheel, is opened

and the sheaf dropped down outside of the frame. The gripping or clamping arms remain open, while by the gear described 70 L-shaped arm is revolved, and they remain open during a half-revolution until brought to the platform upon which the grain from the harvester is thrown and is caught by said clamping-arms. After taking up the gavel 75 from the platform the arms, by the action of the cam, are closed, and the revolution is continued until the gavel has been carried one and a half time around the twisting mechanism, which, it will be understood, is rapidly revolving. As said mechanism revolves it takes from the gavel a continuous series of grain, which is rapidly twisted into a band, as will be apparent. By this time the open space of the gear 6 is opposite the small pinion 18, and the drive-wheel passes on without producing any further revolution. The lug 9 has now arrived in contact with the cam-recess of the tucker-arm, and first raises the arm, forcing the finger against the band 80 and forcing the band into the sheaf or gavel. A continuous movement of the lug brings it in contact with the shoulder at the end of the cam-recess and so reciprocates the tucker-arm that the tucking-finger is forced lengthwise the gavel, and thus the band is tucked 85 under that portion which encircles the gavel. As the lug passes beyond the shoulder and the tucker-arm ceases to be further influenced by the lug, the coiled spring returns the 90 tucker-arm quickly to its original position. At this moment the teeth of the gear 6 re-engage the pinion, and the operation again commences. As the mechanism is started, the clamp-arms reopen and discharge the gavel, 95 now a sheaf complete, and said arms come around to take a fresh supply of grain. The cam upon the end of the arm is a loose cam, and is so geared that the cam portion thereof 100 comes opposite the cam-arm of the rock-arm 105 at every alternate revolution of the clamping-arms. It will thus be seen that one and one-half revolution of the crank-arm is necessary to place the band around the gavel, and when the clamping-arms are stationary the tucking 110 mechanism begins. The band is made by the twisters, which are rotated under the gavel as said gavel travels in a circular path, the bent or curved point 33 of the inner twisting-section taking up a few strands of straw at each 115 revolution and rapidly forming the same into a band subsequently drawn out from the twisters by the revolution of the gavel.

Having described my invention, what I claim is—

1. In a grain-binder attachment, the combination, with the gavel-carrying arms, of the band-twisting mechanism consisting of a fixed and movable tubular section, one mounted within the other and each spirally slotted in a direction opposite to that of the other, and means for rotating said movable section, substantially as specified.

2. In a grain-binder attachment, the com-

5 bination, with a band-twister consisting of a fixed and movable tubular section, one mounted within the other and each spirally slotted opposite to that of the other, and means for rotating said movable section, of a revolving L-shaped arm, a rock-shaft journaled in the arm, a pair of clamping-arms located side by side and one of the same mounted upon the rock-shaft, a cam-arm located at the opposite 10 end of the shaft, a cam-wheel located at the end of the L-shaped arm, and a coiled spring encircling the shaft and adapted to retain the cam-arm upon the cam-wheel, substantially as specified.

15 3. In a grain-binder attachment, the combination, with twisting mechanism consisting of a fixed and a movable tubular section, one mounted within the other and each spirally slotted in a direction opposite to that of the other, and means for operating the same, of a shaft journaled opposite said twisting mechanism, a pulley loosely mounted on the shaft, an L-shaped arm fixed to the shaft, means for revolving the shaft, independent 20 means for revolving the pulley faster than the shaft, a cam located at one side of the pulley and fixed thereto, a rock-shaft journaled in the L-shaped arm, a cam-arm extending from one end of the shaft and resting upon the cam-wheel, a coiled spring encircling the shaft and secured to the same and to the L-shaped arm, a fixed clamping-arm secured to the inner end of the L-shaped arm, and a movable clamping-arm fixed to the rock- 25 shaft, substantially as specified.

30 4. In a grain-binder attachment, the combination, with a band-twisting mechanism consisting of a fixed and a movable tubular section, one mounted within the other and each spirally slotted in a direction opposite to that of the other, a gavel-forming revolving arm located in front of the same, and a tucking device located at one side of the twister, of mechanism for simultaneously operating the twister and gavel-forming arm and intermittently and subsequent to said operations operating the tucking-arm, substantially as specified.

35 5. In a grain-binder attachment, the combination, with the twisting and gavel-holding mechanisms, of the pivoted reciprocal tucker-arm, the lower edge of which in rear of its forward end is provided with a recess which terminates at its rear end in a shoulder, and a disk mounted for rotation below the tucker and having a lug adapted for contact with the lower edge of the arm at and in front of said recess, to thus elevate the arm, and adapted to come in contact with the shoulder and reciprocate the arm after such elevation, substantially as specified.

40 6. In a grain-binder attachment, the combination, with the inner and outer twisting-tubes oppositely and spirally slotted and

means for operating the same, of the tucker-arm longitudinally slotted near one end, a stud passing through the slot and into the frame, said tucker-arm being laterally bent around the under side of the twister and terminating in a tucking-finger, a spring for throwing the tucker in one direction, and a cam-pulley having a cam-stud located one side of said arm and adapted to come against a cam-surface formed in the under side of the arm, and adapted to thereby raise and reciprocate the same against its spring, substantially as specified.

45 7. In a grain-binder attachment, the combination, with the oblong frame, the main shaft journaled transversely therein, a drive-pulley, a gear having a partially-toothed surface, and a cam-pulley, all mounted upon the shaft, a longitudinal shaft arranged at right angles to the main shaft and terminating at its opposite ends in gears, a sprocket-pulley 50 and a beveled gear located upon said longitudinal shaft between its bearings, a countershaft located one side of the main shaft, a pinion mounted on said shaft and engaged by the gear on the main shaft, and a beveled gear mounted upon the inner end of the countershaft and engaging the beveled gear of the longitudinal shaft, of the standard 55 37, the shaft mounted therein, a gear and a sprocket-pulley mounted on the shaft, a chain 60 connecting said pulley with the pulley of the longitudinal shaft, a cam located one side of and rigid with said pulley, an L-shaped arm secured to the inner end of the shaft, a rock-arm journaled in the L-shaped arm, a curved 65 clamping-arm secured to the rock-shaft, a rigid curved arm secured to one side of said clamping-arm, a cam-arm journaled on the opposite end of the shaft and spring-pressed against the cam, a gear connecting the gear 70 of the longitudinal shaft with the gear of the arm-carrying shaft, a bearing located opposite the curved arms, a short shaft mounted therein, a small pinion mounted on the outer end of the shaft, a gear-wheel connecting 75 said pinion with the gear of the longitudinal shaft, a spirally-slotted tube secured to the inner end of the shaft and terminating at its outer end in a finger, an outer tube spirally slotted and encircling the first-mentioned 80 tube, and a tucking-arm slotted in its rear end and mounted over a stud, said tucker-arm terminating in a tucking-finger and provided below the same with a cam-surface 85 adapted to be operated by the cam of the main shaft, substantially as specified.

85 In testimony that I claim the foregoing as my own I have hereto affixed my signature in presence of two witnesses.

JOHN G. GILMER.
